RATION OF MASSACHUSETTS.

METHOD OF INSEAMING SHOES.

1,276,816.

Specification of Letters Patent. Patented Aug. 27, 1918.

Application filed November 14, 1914. Serial No. 872,230.

To all whom it may concern:

Be it known that we, WILLIAM IRVING RYAN and FERNANDO P. AYER, of Manchester, in the county of Hillsborough and State of New Hampshire, have invented certain new and useful Improvements in Methods of Inseaming Shoes, of which the following is a specification.

The present invention relates to a step in the operation of shoe making and has reference particularly to that part of such operation which consists in joining the upper, inner-sole and welt of a welt shoe after the upper has been lasted, this step being technically known as "inseaming."

In order to explain our invention most readily, it may be well to state that in the process of making welt shoes, now extensively used, known as the Goodyear process, the step following the lasting of the sides of the upper is to place a wire around the gathered-in edge of the upper at the toe running from a point near the seam of the cap or tip at one side of the shoe bottom to a corresponding point at the other side, and to secure the ends of this wire by means of anchor tacks which are driven into the innersole through the upper and remain in the shoe either permanently or at least until after the inseaming operation by which the welt and the upper and the innersole are sewed together. Our object is to improve and modify the steps of shoe making in such a way that the toe wire and anchor tacks above referred to may be removed before carrying out the inseaming step, so that certain advantages may be secured and certain objectionable effects obviated, as pointed out more at length in the following specification.

Briefly stated, the principal feature of our invention consists in binding or securing the toe part of the lasted upper in place by means of a plastic composition and then removing the anchor tacks and toe wire, the upper being properly retained in lasted condition by means of the plastic composition referred to, and then applying the welt and sewing the inseam.

50 In the accompanying drawings,—

Figure 1 is a plan view of the bottom of a shoe showing the condition of the shoe after lasting with the aid of a toe wire.

Fig. 2 is a similar view showing the con-

dition after adhesive has been applied to the gathered edges of the upper and the toe wire removed.

Fig. 3 is a similar view of the shoe after the inseaming operation has been completed following our improved method.

Fig. 4 is a perspective view illustrating the step of applying plastic composition to the edge of a lasted upper at the toe part thereof, and illustrating also a suitable form of apparatus which may be used in carrying out this step.

Fig. 5 is a plan view of the bottom of a shoe on which the inseaming operation has been carried out in the old manner, illustrating one of the objectionable effects which our invention overcomes.

Fig. 6 is a detail view representing a longitudinal section through the toe of the shoe and showing a fragment of the last with the innersole, the upper, a toe wire, and the plastic binding composition thereon.

The same reference characters indicate the same parts in all of the figures.

Referring to the drawings which show a lasted shoe in bottom plan view,—a represents the innersole, b represents the lasted upper, and c represents the edges of the upper, lining and box toe or stiffener in a manner such as to illustrate conventionally the way in which such edges are gathered in at the bottom of the shoe adjacent to the toe thereof. d represents the retaining wire or tape, which is commonly called the "toe wire" and which is passed about the toe part of the shoe close to the bottom thereof and outside of the edges c of the upper. In the following description, the wire of tape d will be referred to by the term "toe wire" for the purposes of description and without any limiting significance. e represents the anchor tacks by which the ends of the toe wire are secured at points sufficiently far removed from the tip of the shoe for the required purpose. The use of a toe wire for the purpose described and the manner of its attachment as shown in Fig. 1, being well known and understood, there is no need for a detailed description of the same here, particularly as our invention does not involve any change in the method of applying the toe wire and anchor tacks or in the function of such wire and tacks. f, f, f represent the tacks which are applied during the

lasting operation for temporarily holding the upper at the sides of the shoe until the toe is lasted, these tacks being drawn after the completion of the lasting operation and before the inseaming operation, being replaced by two side tacks *g* as shown in Fig. 2.

Heretofore in making welt shoes, it has been the practice to attach the welt and 10 stitch the inseam while the toe wire and anchor tacks remain in place in the position shown in Fig. 1. The use of the toe wire is of advantage in that it makes it unnecessary to put a large number of tacks around 15 the toe of the shoe to keep the upper from pulling away after being lasted and before sewing on the welt, but the wire and the anchor tacks have been the cause of much difficulty in the operation of sewing on the 20 welt on account of the liability of being struck by the needle of the sewing machine and the necessity on the part of the operator of such machine to endeavor to avoid the wire and tacks when stitching on the welt. 25 Under the best circumstances, the necessity of dodging the anchor tacks in sewing the inseam caused the seam to be more or less uneven, either crooked, high or low. The effect on the seam, caused by the presence 30 of the anchor tacks, is illustrated in Fig. 5 where a welt *h* is shown secured to the shoe by a seam *i*. The displacement of the inner edge of the welt, caused by the presence of the anchor tacks, is indicated at *j* 35 and the uneven or crooked character of the seam occasioned by the effort to avoid the anchor tacks is indicated by the offsets at *k*. As the inseam is a fundamental of the finished shoe which is depended on as a guide 40 in the subsequent steps of bottoming and finishing the shoe, any unevenness in the inseam or any error in its location has an effect of impairing the fit and appearance of the shoe.

45 In case the operator of the inseam stitching machine does not succeed in avoiding the wire and anchor tacks, needles are broken; the welting, upper and innersole are frequently damaged; and there is increased cost in the manufacture due to the 50 labor of resewing and the loss of time consequent upon stopping in the middle of the seam to go back and resew or set a new needle, and there is of course the item of the cost 55 of additional thread and new needles to replace the broken ones.

By our improved method, after the upper has been lasted and the toe wire secured as above described, a plastic binding substance is applied to the gathered-in edges of the upper at the toe end for the purpose of holding the upper in the lasted condition and making unnecessary the retention in place of the toe wire for that purpose.

60 65 Any one of many compositions may be used

for this purpose, it being sufficient that the composition should be fluid or semi-fluid in one condition of temperature and should be solid and relatively rigid in another condition or state. Without limiting the invention to the use of any particular plastic composition, we may say that we have used with success a waxy composition made of paraffin, rosin and cinnabar wax. Preferably we use a mixture consisting of three parts 70 paraffin and one part rosin. However, any substance which will be liquid or semi-liquid when hot and will harden when cold is within the contemplation of this feature of our invention, and so also will any substance which is fluid when wet or moist and hard when dry. The plastic substance or composition, having the characteristics above indicated, is applied upon and around the gathered-in edges of the toe part of the 75 upper in such a way and in such quantities that, after hardening, it will overcome the tendency of the material of which the upper is made to depart from the condition or form given to it by the lasting operation, 80 so that the upper will retain such form even after the toe wire has been removed. It might be stated at this point that any material, having such cohesive or adhesive properties as to secure this effect, may be 85 used within the purview of this invention and within the scope of the appended claims in carrying the invention into effect.

After the composition referred to has 90 been applied and allowed to set or harden to the necessary degree, and after the anchor tacks and toe wire have been removed, the welt is sewed at the inseam in the usual manner or in any other desired way.

The successive steps are shown in Figs. 1, 100 6, 2, and 3, respectively; Fig. 1 representing the shoe bottom before application of the plastic composition; Fig. 6 showing the condition 105 after application of the composition and before removal of the toe wire; Fig. 2 showing the shoe bottom after removal of the toe wire; and Fig. 3 showing it after 110 application of the welt and stitching of the inseam.

Fig. 4 illustrates an apparatus by which 115 the plastic composition may be applied, and also illustrates the step of applying such composition. This apparatus comprises a tank *l* containing the plastic composition, which is heated by a steam coil *m* in the 120 tank and thereby retained in the fluid state. A delivering roll *n* dips into the plastic composition and is rotated by any desired means. The shoes are held against the side of that 125 part of the roll which rises above the plastic material and are moved back and forth as may be necessary to apply the substance at the desired points, the moving roll then raising the material from the tank and depositing it on the portions of the shoe which 130

come into contact with the roll. In applying the composition as above indicated, the projecting edges of the upper material beside the stitching rib of the innersole, and 5 also the rib itself are laid on the applying roll, so that the composition is applied to these parts only of the shoe. The fluid composition penetrates the spaces between the folds or gathers of the upper, and enters 10 the body of such parts thereof as may be absorptive, particularly the woven fabric lining material. It may also be applied in a body on the outer side of the gathered edges and in the groove made by the toe 15 wire, although not necessarily, and generally sufficient stiffness is given by the composition when applied to impregnate and fill the interstices of the material, without coating the outer surface of the upper leather. 20 Whether the composition, upon hardening, stiffens the upper material by impregnating the same, or by coating and incasing it is not important to the invention here claimed, the essential feature of which is that the 25 composition stiffens and holds said gathered edges in place after the toe wire has been removed. Consequently in the claims hereto annexed, such terms as "covering", "surrounding", "enveloping", and words of similar import are intended to mean coating, 30 covering, or impregnating parts of the edges referred to, or of the material thereof, to the extent that the results described will be accomplished; and said terms, as here used, 35 have no further limiting significance. Any other suitable mode of and means for applying the plastic material may be used within the scope of our invention.

It is evident that, as the toe wire and anchor tacks are not in the shoe when the welt is stitched to the inseam, the objectionable effects, occasioned by the toe wire and anchor tacks, are avoided, with the result that the operator of the sewing machine, is enabled to run the seam in the desired location without deviation from the smooth and even line which is so desirable. The operator, being spared the need for taking care to avoid the anchor tacks, can run the seam more rapidly than heretofore, and there is of course no danger of breaking the needle or of damaging any part of the shoe from the causes arising as heretofore explained as a result of retaining the anchor tacks in the shoe.

Among the advantages resulting from our improvement hereinbefore described may be named the following:—decreased labor in the welting operation; increased production; greater accuracy and positiveness of results in sewing on welts; decreased cost due to spoiling the welting; decreased cost for thread; decreased cost of innersoles spoiled in the process of sewing on the welt; 60 decreased loss of time; reduced costs of lasts

due to the fact that shoes can be sent to the inseaming operation sooner after lasting than heretofore; a saving in the amount of leather used, for a narrower welt can be used because the inseam can be made more even 70 and it is unnecessary to have the welt wide enough to allow for crooked and otherwise variable seams; decreased cost of cobbling after welting to patch up and mend the damage done by the welter; reduced difficulty in performing subsequent operations such as rounding, Goodyear stitching and edge trimming; and a greatly improved appearance in the finished shoe.

We claim:—

1. The improvement in the method of making shoes which consists in lasting a shoe in such manner that the edges of the upper adjacent to the toe project away from the plane of the shoe bottom, and then binding such edges in place by application thereto of a coating of plastic composition which has the property of becoming hard with lapse of time and is penetrable by the needle of a sewing machine.

2. That improvement in shoe making which consists in applying to the edge of the toe part of a lasted upper, after the same has been bound in such condition by a toe wire, a plastic substance having sufficient firmness after it has become set to retain the upper in that condition, and removing the toe wire and the anchoring means for the same before proceeding with the subsequent steps of the shoe making processes.

3. The new method of shoe making which consists in lasting the upper, binding the toe part of the upper by means of a wire passed about the gathered-in edge of such toe part and securing said wire by anchor tacks to the shoe, covering and surrounding such gathered edge with a plastic substance, removing the anchor tacks and wire, and stitching a welt to the upper and innersole.

4. The improvement in shoe making which consists in lasting and gathering in the toe part of the shoe upper so that the edges of such part project away from the bottom of the last, enveloping the gathered edges of the upper at the bottom of the shoe in a plastic substance which has the property of hardening or setting into a sufficiently rigid condition to retain such edges in the position given them in lasting, and then stitching the upper and innersole together.

5. The improvement in shoe making which consists in lasting the upper, applying a temporary retaining means to a part of the upper to hold such part in lasted shape, enveloping the edge of such part, where such edge is gathered in at the shoe bottom, in a plastic substance which has the property of hardening after application, and removing said temporary retaining means.

6. The improvement in shoe making which consists in lasting the upper, applying a temporary retainer to the toe part of the upper at the bottom of the shoe to hold such part in the lasted shape, applying a body of heated composition which is plastic when heated and has sufficient firmness when cool to resist the tendency of the upper to withdraw from the lasted shape to the edge of such toe part and in the space between said edge and the shoe bottom, allowing such composition to cool and harden, and removing the temporary retainer.
7. The improvement in the method of shoemaking which consists in lasting a shoe and at the same time so gathering the toe part of the shoe upper that the edge of such part projects outwardly from the bottom of the last, enveloping said gathered edges in a plastic composition which has the property of becoming hard after lapse of time, and passing stitches through such

edge of the upper, the rib of an innersole, and the edge of a welt, to form the inseam of the shoe.

25

8. The improvement in shoemaking which consists in lasting a shoe and gathering the toe part of the upper about the toe of the last in such manner that the edges of the upper project away from the bottom of the last, enveloping such edges at the toe part in a heated plastic composition which has the property of hardening when cool, and finally stitching or sewing the inseam of the shoe through the edges of the upper, including the portion thereof thus enveloped in such composition.
